UNITED STATES PATENT OFFICE

THEODORE BODDE, OF ROCHESTER, NEW YORK, ASSIGNOR TO GENERAL RAILWAY SIGNAL COMPANY, OF ROCHESTER, NEW YORK

AUTOMATIC TRAIN CONTROL SYSTEM

Application filed May 16, 1929. Serial No. 363,531.

This invention relates to automatic train control systems, and more particularly to train control systems of the shoe and ramp type.

5 In applying automatic train control to existing railway signalling systems, it is desired to communicate automatically, from the trackway to the moving vehicle, the conditions of traffic existing ahead of such vehicle. Irrespective of whether home and distant signal indications are used, or whether three indication condition type signals are used, in which clear, caution, and danger are indicated to the engineer of the 10 train, it is desirable to manifest on the car at least three kinds of traffic conditions, conventionally called clear or proceed, caution and danger or stop traffic conditions. In order to transmit a plurality of distinctive 15 control influences from a single ramp to a moving railway vehicle, it is necessary to make the ramp distinctive under the various conditions of traffic.

In accordance with the present invention 20 it is proposed that the presence of the ramp itself be manifested on the car by lifting a shoe located on that car, and to give the ramp two other distinctive characteristics by connecting a rectifier between such ramp 25 and the track rails, so that through the medium of contact between a car-carried shoe and the ramp the direction of valve action of the rectifier may be determined on the car.

More specifically, it is proposed in accordance 30 with the present invention to employ a polyphase induction type relay on the railway vehicle, having two windings connected in multiple branches and each winding including a rectifier, in series therewith, these 35 rectifiers having their valve action poled oppositely, and having these multiple branches connected in series with a source of alternating current between the car-carried shoe and the axle of the vehicle, whereby for reasons 40 pointed out hereinafter this car-carried relay will assume a position depending on the direction of the action of the rectifier valve between the ramp and the track rail.

Other objects of the invention reside in 45 the provision of an audible signal that is sounded during each passage of the car-carried equipment over a clear or proceed ramp, the provision of means to effect a 50 brake application that may be easily annulled by the engineer upon the passage over a caution ramp and the provision of means to cause the brakes to be applied, in such a manner that they cannot be easily released, upon passage of the vehicle by a stop ramp.

Other objects, purposes and characteristic 55 features of the invention will appear in part as the description thereof progresses, and will in part be obvious from the accompanying drawing.

In describing the invention in detail, reference 60 will be made to the single accompanying drawing in which one embodiment of the present invention has been illustrated.

Trackway apparatus.—Referring particularly to the trackway apparatus, the rails 1 of a double-track railway system, in which traffic normally moves from left to right in the direction of the arrow, is divided by insulating joints 2 into blocks of which the block I and the adjacent ends of two other blocks H and J only have been illustrated. At the entrance to each block is provided a suitable signal Z, having a distinctive exponent, which signal for convenience has been illustrated as a semaphore signal having 70 the usual 45 degree and 90 degree circuits, which circuits for the signals Z and Z¹ are energized from the batteries 4 and 4¹ through contacts of the polar track relays T and T¹. There is also provided at each signal location 75 a repeater relay RR, which is energized only when the corresponding track relay T is energized to its right hand clear position; this repeater relay RR through its contacts 6 and 7 pole changes the rectifier 8 in accordance 80 with the energization of the repeater relay RR, this rectifier 8 being connected between the track rails 1 and the track ramp TR through the medium of a semaphore contact 9 and a track relay contact 10. This semaphore contact is operatively connected to the semaphore signal blade by suitable means conventionally shown by the dotted line 14. From this construction of the trackway apparatus, it appears that under clear traffic 85

- conditions the semaphore signal will be at proceed and the rectifier 8 will be connected between the track rails and the track ramp in a manner to permit the flow of current 5 from the track rails 1 to the track ramp TR; when the block J in advance is occupied the track relay T¹ will assume its de-energized position, thereby moving the signal Z¹ to its stop position and applying current of negative polarity 10 from the track battery 11¹ to the track rails of the block I, and thereby causing the track relay T to assume its left hand energized position effecting de-energization of the repeater relay RR and movement 15 of the signal Z to the caution position, whereby the rectifier 8 will be connected in a circuit to permit the flow of direct current from the ramp TR to the track rails 1. It is thus seen, that the pole-changer contacts 20 12 and 12¹ assume their normal positive polarity position through the medium of an operative connection indicated by dotted lines 13 and 13¹, when the corresponding signal assumes the clear or caution position, but 25 this pole-changer assumes the negative position when such signal assumes the stop position. Further, it is obvious that with the track relay T de-energized, as is the case when the block I is occupied, the track ramp 30 TR will be disconnected from the track 1 through the medium of the contact 10 of the track relay T, and also under this condition of traffic the semaphore contact 9 will break the ramp circuit.
- 35 *Car-carried apparatus.*—On the railway vehicle is carried a shoe 20 adapted to contact with a trackway ramp TR, TR¹, etc. during the passage of the car by a signal location. This shoe 20 not only contacts with these 40 ramps TR, but also is raised during such contact with the track ramps, thereby opening the contacts 21 and 22 and closing the contacts 23 and 24. The car-carried equipment also includes a turbo-generator G, adapted to 45 generate direct current, as conventionally illustrated by commutator 25, and to generate alternating current as illustrated by the slip rings 26, which slip rings 26 are connected to a transformer 27. The car-carried apparatus 50 also includes a main relay MR of the polyphase inductive type, and two neutral stick relays CA and CL for manifesting clear and caution traffic conditions, respectively, and further includes a slow-dropping signal 55 relay SR, audible signals BL and W, and a suitable normally energized brake control device EPV.
- Attention is directed to the fact that the windings 30 and 31 of the two-element inductive type relay MR are connected in multiple, that the winding 30 has connected in series therewith a rectifier 32, whereas the winding 31 has connected in series therewith a rectifier 33, and that these rectifiers have 60 their rectifying valve characteristics con-

nected oppositely in these two branch circuits, the purpose for which will be described hereinafter. The car-carried apparatus also includes an annulling push button AN, and a reset push button RS. It is believed that 70 the construction as well as the operating characteristics of the system are most readily explained by considering the operation of the system.

Operation.—Under normal clear traffic 75 conditions of the car-carried apparatus, that is, when the railway vehicle 35 is moving along the railway track between the ramps when such vehicle has just passed a clear ramp, namely, when the railway vehicle is moving in a clear block, the caution relay CA and the clear relay CL are respectively energized through the following stick circuits:—(1) beginning at the plus bus wire 36, contacts 21, wires 37, 38, and 39, stick contact 40 of the relay CA, wires 41 and 42, lower winding of the relay CA, wires 43 and 44, to the minus bus; and (2) beginning at the plus bus, wire 36, contacts 21, wires 37, 38, 46, and 47, stick contact 48 of the clear relay 80 CL, wire 49 and 50, lower winding of the clear relay CL, wire 51, and 44, to the minus bus.

With the relays CA and CL both energized the electro-pneumatic brake control device 95 EPV is energized through the following circuit:—beginning at the plus bus, wires 52 and 53, contact 54 of the reset push button RS, wires 55 and 56, contacts 22 of the shoe 20, wire 57, contact 58 of the caution relay CA, wire 59, contact 60 of the clear relay CL, wires 61 and 62, normally closed contact 63 of the annulling push button AN, wire 64, winding of the electro-pneumatic valve EPV, wire 65 to the negative bus. It is thus seen 100 that the electro-pneumatic valve is maintained energized under the conditions stated, thereby holding suitable pneumatic operated 105 brake control apparatus in its inactive condition, said valve if de-energized causing an 110 automatic application of the brakes of the railway vehicle.

Let us now assume that the railway vehicle represented by the wheels and axle 35 passes a caution ramp. As the shoe 20 engages the track ramp TR it opens the shoe contacts 21 and 22 and closes the shoe contacts 23 and 24. It may be pointed out here, that the contacts 21—23, as well as contacts 22—24 are preferably make-before-break 115 contacts, that is, contacts 23 and 24 are closed before contacts 21 and 22 are opened, and vice versa. With the shoe contacts 22 opened and shoe contacts 24 closed, the electro-pneumatic valve EPV is maintained energized 120 through the following circuit:—beginning at the plus bus, wires 52 and 53, contact 54 of the reset push button RS, wires 55 and 66, shoe contacts 24, wires 67 and 62, dash pot retarded contacts 63 of the annulling push 125

button AN, wire 64, winding of the device EPV, wire 65, to the minus bus. It is thus seen that the brake control device EPV is maintained energized so long as the shoe 20 is raised irrespective of the energized conditions of the relays CA and CL. Under this condition with the shoe 20 riding on the ramp TR under caution traffic conditions, pulsating current may flow from the secondary winding of transformer 27 through wire 68, shoe 20, ramp TR, wire 69, back contact 6 of the repeater relay RR, wire 70, contact 10 of the track relay T, wire 71, rectifier 8, wire 72, semaphore contact 9, wires 73 and 74, back contact 7 of the relay RR, wire 75, track rails 1, wheels and axle 35, wire 76, winding 31, rectifier 33, back to the secondary winding of transformer 27. It will be noted that the rectifiers 8 and 33 in the circuit just traced have their valve action poled in the same direction, thus permitting the flow of pulsating current in the direction in which the circuit was traced. Also, it is understood that the circuit just traced is of rather low resistance and of rather high inductance, so that a comparatively large pulsating current will flow, this pulsating current lagging considerably behind the voltage of the secondary winding by reason of the inductive characteristic of the circuit just traced. There is, however, another circuit present, while the shoe 20 is on the caution ramp, which other circuit is exactly the same as the one just traced except that it includes the branch of the main relay MR including the winding 30 and the rectifier 32 in series, instead of the branch including winding 31 and rectifier 33. This latter circuit, it will be noted, has its rectifiers 32 and 8 poled oppositely, so that the rectifier 32 during one wave of an alternating current cycle will restrict the flow of current and the rectifier 8 will similarly restrict the flow of current during the other wave of such cycle, or in other words, the resistance of the circuit through the winding 30 of the main relay MR is bi-directional and rather high, and therefore restricts the flow of current appreciably and in one direction as well as in the other, so that the small amount of alternating current which will flow in this latter circuit including the ramp TR will flow substantially in phase with the voltage of transformer 27. With a small amount of alternating current of unity power factor flowing in the coil 30 of the main relay MR and a comparatively large lagging pulsating current flowing in the other winding thereof, a torque is produced in the rotor of the relay MR; this causes the contact 80 to be moved to the left hand position to complete the following pick-up circuit for the caution relay CA, this caution relay as well as the clear relay CL both having assumed their de-energized position in response to lifting of the shoe 20, because the stick circuits for both of

these relays were then opened by opening the shoe contact 21:—beginning at the plus bus, wire 81, shoe contact 23, wire 82, polar contact 80 of the main relay MR, assuming its left hand position, wire 83, winding of the caution relay CA, wires 43 and 44 to the minus bus. As the shoe 20 moves off the track ramp TR the stick circuit for the caution relay CA, and including the normally closed shoe contacts 21, heretofore traced is again closed thus maintaining the caution relay CA energized.

With the caution relay CA energized and the clear relay CL de-energized, the shoe 20 having left the track ramp TR, the electro-pneumatic valve EPV is de-energized, because the contact 60 of the clear relay CL is now in its de-energized position, thereby sounding the whistle W, to advise the engineer that he will obtain a brake application unless he operates his annulling push button AN. The circuit for the whistle valve may be traced as follows:—beginning at the plus bus, wires 52 and 53, contact 54, wires 55 and 56, contact 22, wire 57, contact 58, wire 59, contact 60 of the clear relay CL in its lower position, wire 84, winding of whistle valve W, wire 85 to the minus bus.

The engineer may now by depressing his push button AN pick up the clear relay CL and re-energize the brake control device EPV before the brakes are actually fully applied, by closing the following circuit:—beginning at the plus bus, wire 36, contacts 21, wires 37, 38, 46, and 87, contacts 88 of the push button AN, wires 89, 90 and 50, lower winding of the clear relay CL, wires 51 and 44, to the negative bus. As soon as the clear relay CL has assumed its energized position, its stick circuit heretofore traced is closed, thus maintaining this relay energized, and if the engineer then moves his annulling push button to its normal position before the contact 63 has had an opportunity to open, this contact 63 being a time-controlled contact which opens if the annulling push button AN is depressed, for say more than 15 seconds, the device EPV will again be energized through the circuit heretofore traced.

Let us now assume that the railway vehicle in question, equipped with the car-carried apparatus embodying the present invention, passes a danger ramp (a ramp entirely disconnected from the track rails) under which condition the caution relay CA and the clear relay CL will again be de-energized for reasons heretofore given, the device EPV being maintained energized so long as the shoe 20 is lifted. Since, under this condition, the main relay MR will not be energized by current of any kind, because the circuit including the ramp and main relay MR is now open at the contact 10 of the track relay T, neither the relay CA nor the relay CL will be energized. As the shoe 20 leaves the ramp during pas-

sage of that vehicle by such ramp the temporary circuit including shoe contacts 24 for the device EPV is broken, and the device EPV will assume its de-energized position and effect a brake application. If the engineer is alert and decides it to be safe to allow the train to again proceed before coming to a full stop, he may depress the reset push button RS not conveniently accessible, but accessible to the engineer only after a certain amount of annoyance and inconvenience.

Such depression of the reset push button RS effects shunting of the stick contact 40 of caution relay CA by the contact 92 of the reset push button and also the shunting of the stick contact 48 of the clear relay CL by closure of the contact 93 of the reset push button RS, so that the caution relay CA and the clear relay CL will assume their energized position, and thereafter remain energized through the stick circuits heretofore traced. If the engineer immediately returns his reset push button RS to normal it will effect closure of the contact 54 thereof, thereby re-energizing the device EPV through the circuit for this device heretofore traced. Attention is particularly directed to the fact that de-energization of the device EPV under danger traffic conditions, as just explained, does not effect sounding of an audible signal, so that the engineer must actually be on the alert to avoid a brake application under danger traffic conditions, whereas de-energization of the device EPV under caution traffic conditions as heretofore explained is accompanied by the sounding of the whistle W, and re-energization of the device EPV may be obtained by depressing the push button AN located conveniently to the engineer.

Let us now assume that the vehicle passes a track ramp under clear traffic conditions, it being assumed that the car-carried apparatus is also in its normal clear traffic condition prior to such passage. As the shoe 20 rides up the incline of the ramp, the shoe contacts 21 and 22 are opened and the shoe contacts 23 and 24 are closed, so that the caution relay CA and the clear relay CL are de-energized, but the device EPV is maintained energized temporarily through the auxiliary circuit including the shoe contact 24. With the shoe 20 engaging the clear ramp TR pulsating current in appreciable quantity may flow through the winding 30 of the main relay MR through the following circuit and in the direction said circuit is traced:—beginning at the secondary winding of transformer 27, rectifier 32, winding 30 of the main relay MR, wire 76, wheels and axle 35, track rails 1, wire 75, contact 7 of the repeater relay RR in its raised position, wire 70, contact 10 of the track relay T, wire 71, rectifier 8, wire 72, semaphore contact 9, wires 73 and 95, contact 6 of relay RR in its raised position, wire 69, ramp TR, shoe 20, wire 68, back to the

secondary winding of transformer 27. For reasons heretofore given the pulsating current in the circuit just traced will be of appreciable value and will lag behind the voltage inducing it, by reason of the inductance characteristic of the circuit. Also, for reasons similar to those heretofore given, there will be a flow of current in another circuit exactly the same as the one just traced, except that it includes the coil 31 of the main relay MR and the rectifier 33 instead of the coil 30 of this relay and the rectifier 32, but the current flow in this second circuit is alternating and comparatively small, because the rectifier 33 is poled oppositely to the rectifier 8, so that the effective resistance of this second circuit is very high and restricts the flow of current in one direction as much as it does in the other, so that a small alternating current substantially in phase with the voltage producing it flows in this second circuit.

With alternating current of substantially unity power factor flowing in the coil 31 of the relay MR and with the flow of pulsating current lagging appreciably behind the voltage producing it flowing in the coil 30 of the main relay MR, a torque will be produced in the rotor of said relay MR tending to operate the contact 80 to its right hand position. This movement of contact 80 closes the following pick-up circuit for the caution relay CA and the clear relay CL beginning at the plus bus, wire 81, shoe contacts 23, wire 82, polar contact 80 of the main relay MR to the right, wire 97, upper winding of the caution relay CA, wire 98, upper winding of the clear relay CL, wire 99, upper winding of the signal relay SR, wire 100, to the minus bus. With this circuit completed the relays CA, CL and SR will all assume their energized position. The relays CA and CL will, as soon as the shoe 20 leaves the ramp TR, have their stick circuits heretofore traced again completed, so as to maintain them energized thereafter.

With the relays CA and CL energized and the shoe 20 returned to its normal position the brake control device EPV is again energized, and by reason of the slow-acting characteristic of the device EPV and the fact that this device is energized so long as the shoe 20 is in its raised position, its valve will not actually be opened when a train passes a clear ramp. In this connection, if desired, the shoe contacts 21—23 and 22—24 may be of the make-before-break type, so that the device EPV is not actually de-energized during the passage of a clear ramp. Energization of the signal relay SR, causes its front contact 101 to close a circuit for the bell BL, readily traced in the drawing, thereby sounding the same and informing the engineer that he has just passed a clear ramp and that his car-carried apparatus is in good working order. In order to sound the clear bell BL for a suf-

5 sufficiently long period of time to properly advise the engineer of the fact that his train control apparatus is in good working order, this relay SR has been provided with a lower 5 or slug winding 102, which is rendered active by close-circuiting the same upon the relay SR assuming its energized position, through the medium of the front contact 103. In other words, the signal relay SR is very quick 10 to pick up, but is very slow to drop, because the slug 102 is effective to retard a change of flux therein between the time of deenergization of the relay SR and its actual dropping.

15 Attention is particularly directed to certain advantages afforded by the system embodying the present invention. In the first place attention is directed to the fact that no wayside source of current is required for energizing the ramps TR as is true of certain ramp systems. In other words, instead of applying a source of current of one polarity or the other between the track rail and the track ramp, a rectifier is applied therebetween, with its valve poled in one direction or the other, this rectifier requiring no particular attention and having an extremely long life. Attention is also directed to the fact that should the rectifier located at a particular track location be short-circuited, for some reason or other, this could not possibly give a false indication on the car, because the current flow in both windings of the main relay MR would in that instant flow 30 in circuits having the same inductance characteristics, so that the current flowing in these windings would produce no torque in the relay MR. Obviously, if an open circuit should occur in the ramp circuit, such as the breaking of wires 69 or 75, a danger indication would be manifested on the train, which, although wrong, would be on the side of safety and would not be as undesirable as a false clear, or false caution indication. Further, 35 should an open circuit appear in one of the multiple paths including windings 30 and 31, current would flow only in one of these windings and no torque would be produced. The system disclosed is one embodying every possible feature of safety, namely, that all signals function on the side of safety and if they produce a false control or indication due to a failure, such control or indication manifests danger, thereby stopping the train unnecessarily rather than letting it proceed due to such failure.

40 The rectifiers 8, 8¹, 32 and 33 are preferably rectifiers of the electrolytic, crystal or copper oxide type in which the rectifying action is inherent in the structure of the device. Rectifiers of the vacuum gap thermal type may also be used if desired, especially if they do not require external heating of one of their electrodes. The rectifiers used shall 45 permit a certain amount of backflow, that is,

leakage in the opposite direction to the valve action, this in order to obtain the alternating current of substantially unity power factor heretofore mentioned. The relay MR should be one of the two-element induction type, and one which will not produce any torque if the current flow in its two windings is exactly in phase, and is preferably one in which the magnetic structure for both windings is the same so that each winding associated therewith has the same inductance as the other winding.

Having thus shown and described one rather specific embodiment of the present invention, it is desired to be understood that the specific apparatus and circuit arrangement selected to illustrate the invention has been selected for the purpose of facilitating disclosure of the nature of the invention rather than its scope or the exact construction preferably employed in practicing the same, and this particular showing is not intended to exhaust all possible embodiments thereof, and it is to be understood that various changes and modifications may be made to adapt the invention to the particular problem to which the invention is to be applied, all without departing from the spirit or scope of the invention or the idea of means underlying the same. For instance, the invention may be applied to a railway system of the manual block type, in which event there will be substituted for the pole changing contacts 6 and 7, a pole changing switch manually operable by the towerman. Also, if desired, the present invention may be applied to systems which set up specific speed limits instead of effecting a brake application which may be annulled by the engineer, or if desired, the invention may be used for transmitting two kinds of traffic condition such as proceed and danger instead of three kinds of traffic conditions, as illustrated. In other words, the present invention is not to be limited in any sense, except as demanded by the scope of the following claims.

45 What I claim as new is:—

1. Trackway apparatus for automatic train control systems comprising; a contact ramp; a rectifier; and means for at times including said rectifier in a circuit branch connecting said ramp and the rail of the railway track to permit the free flow of current from said rail to said ramp, and at other times including said rectifier in said branch to permit the free flow of current from said ramp to said rail.

2. In an automatic train control system; the combination with a railway track and a vehicle movable thereon, of means for communicating control influences from the track to the vehicle comprising a circuit including in series a source of alternating current on the vehicle and a rectifier on the track.

3. In an automatic train control system;

the combination with a railway track and a vehicle movable thereon, of means for communicating control influences from the track to the vehicle comprising; an electro-responsive means on the car; and a circuit including in series said electro-responsive means, a source of alternating current on the car, and a rectifier on the track.

4. In an automatic train control system; the combination with a railway track and a vehicle movable thereon, of means for communicating control influences from the track to the vehicle comprising, electro-responsive means on the vehicle responsive to pulsating current but not responsive to alternating current, a source of alternating current connected in series therewith, and means located along the trackway including a rectifier for at all times including said rectifier in series with said source and electro-responsive means.

5. In an automatic train control system; the combination with a railway track and a vehicle movable thereon; and of means for communicating control influences from the track to the vehicle comprising, an electro-responsive means on the vehicle distinctively responsive to pulsating currents of different polarity but not responsive to alternating current, a source of alternating current connected in series therewith, and means located along the trackway including a rectifier for at times including said rectifier in series with said source and electro-responsive means in a manner to permit pulsating current to flow through said electro-responsive device in one particular direction and at other times connecting said rectifier in series with said source and electro-responsive means to permit the flow of pulsating current in the opposite direction through said electro-responsive means.

6. In an automatic train control system; the combination with a railway track and a vehicle movable thereon; of means for communicating control influences from said track to said vehicle comprising; vehicle carried apparatus including an electro-responsive device responsive only to pulsating current, a source of alternating current connected in series therewith; trackway apparatus including a rectifier; and means partly on the track and partly on the vehicle for at times conductively connecting said rectifier in series with said source and electro-responsive device.

7. In an automatic train control system; the combination with a railway track and a vehicle movable thereon; and of means for communicating control influences from the track to the vehicle comprising; vehicle carried apparatus including two car-carried coils connected in multiple, a rectifier in series with each coil, said rectifiers having their valve action reversed in the multiple circuits

including said coils, a source of alternating current connected in series with said multiple circuits; trackway apparatus including a trackway rectifier; and means partly on the track and partly on the car for connecting said trackway rectifier in series with said source and said coils in multiple.

8. In an automatic train control system; the combination with a railway track and a vehicle movable thereon; and of means for communicating control influences from the track to the vehicle comprising; vehicle carried apparatus including a polyphase induction type relay having two windings connected in multiple, a rectifier included in series with each of said windings in a manner to permit the free flow of current in one direction in a circuit including said coils in multiple through one coil and permit the free flow current in the other direction in such circuit through the other coil, a source of alternating current connected in series with said multiply arranged windings; trackway apparatus including a trackway rectifier; and means partly on the vehicle and partly on the track for at times connecting said trackway rectifier in series with said relay and source of current.

9. In an automatic train control system; the combination with a railway track and a vehicle movable thereon; and of means for communicating control influences from the track to the vehicle comprising; vehicle carried apparatus including a polyphase induction type relay having two windings connected in multiple, a rectifier included in series with each of said windings in a manner to permit the free flow of current in one direction in a circuit including said coils in multiple through one coil and permit the free flow of current in the other direction in such circuit through the other coil, a source of alternating current connected in series with said multiply arranged windings; trackway apparatus including a trackway rectifier; and means partly on the vehicle and partly on the track for at times connecting said trackway rectifier in series with said relay to permit the free flow of current in one direction through said relay and at other times connecting said trackway rectifier in series with said source and relay to permit the free flow of current in the opposite direction.

10. In an automatic train control system, the combination with a railway track divided into blocks and a vehicle movable thereon; of communicating means including a source of energy on the vehicle for communicating clear, caution, and stop traffic conditions through the medium of said source from the trackway to the vehicle intermittently upon the entrance of the train into blocks, means controlled by said communicating means for sounding an audible signal upon each en-

trance of said vehicle into a clear block, means for applying the brakes in a manner so that the brake application may be annulled by suitable annulling means upon entrance
5 of the train into a caution block, and means for applying the brakes in a manner so that such brake application cannot be annulled by said annulling means but can be reset by suitable means after a certain amount of annoy-
10 ance upon entrance of the train into a stop block.

11. In an automatic train control system, the combination of a railway track and a vehicle thereon; of train control means on
15 the vehicle; a source of energy on the vehicle; a circuit including said train control means, said source, and including part of said rail-
way track; and means along the railway track and included in said circuit for chang-
20 ing the character irrespective of value of the current in said circuit derived from said source in accordance with traffic conditions in advance of said vehicle.

12. In an automatic train control system,
25 the combination of a railway track and a vehicle thereon; of train control means on the vehicle; a source of energy on the vehicle; a circuit including said train control means, said source, and including part of said rail-
30 way track, and means along the railway track and included in said circuit for chang-
ing the character irrespective of value of the current derived from said source into cur-
35 rent of one character or another in accord-
ance with traffic conditions in advance of said vehicle.

13. In an automatic train control system, the combination of a railway track and a vehicle thereon; of train control means, on the
40 vehicle; a source of energy on the vehicle; a circuit including said train control means, said source, and including part of said rail-
way track; and means along the railway track and included in said circuit for either
45 interrupting said circuit or changing the character of the current derived from said source in accordance with traffic conditions in advance of said vehicle.

14. In an automatic train control system,
50 the combination of a railway track and a vehicle thereon; of train control means on the vehicle; a source of energy on the vehicle; a circuit including said train control means, said source, and including
55 part of said railway track; and means along the railway track and included in said circuit for either interrupting said circuit or changing the character of the current de-
rived from said source into current of one character or another in accordance with traffic conditions in advance of said vehicle.

In testimony whereof I affix my signature.
THEODORE BODDE.
